UNITED STATES PATENT OFFICE.

MARIA DOUJAK, OF NEW YORK, N. Y., ASSIGNOR OF PART INTEREST TO CARL HELLER,
OF NEW YORK, N. Y.

WIND-SHIELD.

Specification of Letters Patent.

Patented May 29, 1917.

1,227,595.

Application filed June 21, 1916. Serial No. 105,090.

To all whom it may concern:

Be it known that I, MARIA DOUJAK, a subject of the Emperor of Austria, and a resident of New York, in the county of New York and State of New York, have invented certain new and useful Improvements in Wind-Shields, of which the following is a specification.

This invention relates to improvements in wind-shields, as applied to vehicles, and the principal object of the invention is to provide a wind-shield having an adjustable portion which may be positioned so as to be protected against moisture as from rain or snow, whereby its transparency might be affected.

A second object is to provide such wind-shields in forms readily attachable to existing vehicles as well as new constructions.

These and other objects are attained by the novel construction and combination of parts hereinafter described, and shown in the accompanying drawing, forming a material part of this specification, and in which:

Figure 1 is a perspective view of a conventional type of automobile, showing the application of the invention.

Fig. 2 is an end view of the wind-shield.

Fig. 3 is a vertical sectional view of the same taken, on line 3—3 of Fig. 4.

Fig. 4 is a front elevation of the shield.

Fig. 5 is a perspective view showing the removable bottom wall of the device.

Fig. 6 is a similar perspective view, showing the folding end casings, whereby the movable panel is held extended.

Fig. 7 is another perspective view, showing in detail the hinged, upper panel of the shield.

Fig. 8 is a fragmental perspective view showing a detail of construction, and

Fig. 9 is a similar fragmental detail illustrating the manner of holding the plates in position.

The invention is comprised of a rigid frame having side elements 15, the same being connected by a cross bar 16 at the top, a similar bar 17 being secured at the bottom and provided with means for attachment to the dash board or front portion of the vehicle.

Within the casing are two uprights 20, secured at their tops and bottoms respectively to the rails 16 and 17, forming an in-

terior frame for supporting the transparent plates 22, the edges of which are contained in grooves.

It is to be understood that these plates are permanently affixed, while a swinging central plate 23 is engaged by hinges 24 to the top rail 16, the plate being contained in a frame 25, further engaged by stems having button heads 28, adapted to turn after entering slotted openings 30, formed in the front rail 32 of the bottom plate 33, in such manner that when engaged therewith as to form a rigid structure.

The swinging plate 23 is made of glass or other like transparent material, so that the operator can see clearly through it, thereby being able to direct the vehicle. The bottom plate 33 is stiffened by side flanges 34 extending upward along its outer edges, and has a downturned flange 35 at the extreme front adapted, when in an extended position to engage with the rail 17.

A pair of side plates 40 are held in a triangular frame 42 disposed along edges, and are removably engaged with the upright bars 20, by means of hooks 43 adapted to enter corresponding openings made in the lugs 44 formed with the bars.

In order to prevent the water from reaching the transparent plate 23, a trough 45 is provided at the top of the structure, the same being intended to catch any water which may flow from over the roof of the vehicle, and carry it away to the sides in such manner that it will not interfere with the transparency of the plates employed.

In operation, the plate elements 23 and 33 are placed in the position indicated in Fig. 1, the side plates 40 being secured by the hooks forming a rigid attachment whereby the plates are securely held in their angular position.

The specific use of the device is during storms only, as under normal conditions the plate 23 will occupy the entire opening between the bars 20 and have the usual appearance of an ordinary wind-shield, the lower or bottom plate 33 and triangular side plates 40 being removed and stored in any convenient place with the vehicle.

Having thus described my invention, what I claim as new and desire to secure by Letters Patent, is:

In a wind-shield, the combination with a fixed frame, of a pair of vertical bars divid-

ing said frame into sections, transparent panels secured between the outer elements of said frame and said bars, a central transparent panel hinged at its top to the upper member 5 of said frame, a plate removably engageable with the lower member of said frame, means for engaging said plate to said central panel at one edge thereof, means for engaging said plate to the lower element of said 10 frame, a pair of triangular transparent un-

yielding plates suited to fill the opening between said central panel and said vertical bars when said panel is in an angular position, and means for engaging said triangular plates with said vertical bars.

Signed at New York, in the county of 15 of New York, and State of New York, this 31st day of May, A. D. 1916.

MARIA DOUJAK.
